DESIGN FOR A GREEN PEA SHELLER

Sylvester Q. Harper, Miami, Fla.

Application April 15, 1940, Serial No. 91,678

Term of patent 7 years

To all whom it may concern:

Be it known that I, Sylvester Q. Harper, a citizen of the United States, residing at Miami, in the county of Dade and State of Florida, have invented a new, original, and ornamental Design for a Green Pea Sheller, of which the following is a specification, reference being had to the accompanying drawing, forming a part thereof.

In the drawing:

The figure is a perspective view of a green pea sheller showing my new design.

The other side and rear, not shown, of the article illustrated are substantially plain.

I claim:

The ornamental design for a green pea sheller, as shown and described.

SYLVESTER Q. HARPER.
